MULTIANGULAR MITER ATTACHMENT

Maurice E. Peeples, Kingsland, Ga.

Application June 14, 1948, Serial No. 32,922

1 Claim. (Cl. 7—13)

1

This invention relates to hand saws.

An object of this invention is to provide a combined saw and miter means so that a carpenter may mark and cut the wood with a single tool on a full set of angles normally used by a carpenter.

Another object is to provide a hand saw with a multi-angular marking or angle gauge and square on the opposite sides of the saw blade adjacent the handle for marking and cutting material at different angles, and a rule or linear scale along the top or back edge of the blade, all calibrated to indicate said angles and linear measure for right or left handed use.

A further object of this invention is to provide a combined saw, square and miter which is useable by a right or left handed person, and which will permit the marking of oppositely extending angles by merely flipping the saw over, rather than turning the board over.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing,

Figure 1 is a fragmentary elevation of a hand saw having a miter means secured thereto embodying this invention;

Figure 2 is a sectional view taken on the line 2—2 of Figure 1;

Figure 3 is a sectional view taken on the line 3—3 of Figure 1.

Referring to the drawing, the numeral 10 designates generally an elongated saw blade formed of a body 11 having saw teeth 13 along one lengthwise edge thereof and formed with a straight back edge 12. The body 11 has secured thereto a handle 14 having a forward body 15 provided with a slot 16a within which the rear end of the blade 10 is adapted to be secured. The handle 14 is secured to the blade 10 by means of bolts 16 having countersunk heads 17 and countersunk nuts 18. The blade 10 has fastened to the opposite sides thereof a pair of miter or gauge plates generally designated as 19. These plates 19 are formed with a straight rear edge 20 disposed at right angles to the back edge 12 of the blade 10 and each plate 19 is formed with a right angular rib 21 which provides a right angular shoulder 22 disposed at right angles to

2

the back edge 12. The plate 19 is also formed with an angled shoulder 23 which in the present instance is disposed on an angle of substantially 20° and extends from the upper or back edge of the plate 19 on a downward and rearward inclination. The plate 19 is also formed with a second shoulder 24 disposed forwardly of the shoulder 23 and in the present instance the shoulder 24 is disposed at an angle of substantially 32° being inclined downwardly and rearwardly from the back edge 12. The plate 19 at its forward edge is formed on an angle of substantially 45° as indicated at 25 with the angle 25 extending downwardly and rearwardly from the back edge 12. The two plates 19 are of like construction and are secured to the opposite faces of the blade 10 by means of rivets or fastening members 26 which are countersunk as indicated at 27 at their opposite ends in the plates 19.

15 The upper edges of each plate 19 are formed with graduations 28 which are continuations of graduations 29 formed on the upper or back edge of the blade 10.

20 In the use of this saw, the saw may be used in the conventional manner for cutting through wood and when it is desired to cut the wood on an angle the saw is laid on the wood with one of the shoulders of plate 19 abutting against an edge or end of the board. The board is then

25 marked along the back edge 12 of the saw blade and the board may then be cut along the marked and angled line. With a saw as hereinbefore described, the carpenter will be able to quickly and accurately mark angled lines on the board

30 at either or both ends and it is only necessary to turn the saw over to form oppositely angled lines at each end of the board thereby eliminating the previous practice of turning the board over to form the oppositely angled lines. This

35 saw will provide as a single element a tool which will eliminate the use of both the saw and miter forming means and by providing the mitering means on the rear portion of the saw blade with the mitering means angled downwardly and rearwardly the mitering means will not interfere with the normal use of the saw. Furthermore, this

40 saw will effect a substantial saving in cost of tools for a carpenter in addition to effecting a substantial saving in time in the marking and cutting of angled lines.

45 What is claimed is:

50 In a tool having an elongated blade having a front end and a rear end and formed with one straight edge, a pair of triangular stepped gauge plates disposed adjacent the rear end of said

blade with one right angular edge of each plate parallel with said straight edge and another edge of each plate disposed at right angles to said straight edge, the hypotenuse of each plate extending downwardly and rearwardly from said straight edge, the steps of each plate being arranged at varying angles relative to said straight edge with the lowest step foremost, means rigidly and permanently securing said plates to said blade, a handle projecting from said rear one of said blade and abutting against said right angularly disposed edges of said plates, and means removably securing said handle to said blade.

MAURICE E. PEEPLES.
